UNITED STATES PATENT OFFICE

JOHN ROYDEN PEIRCE, OF NEW YORK, N. Y., ASSIGNOR TO INTERNATIONAL BUSINESS MACHINE CORPORATION, OF NEW YORK, N. Y., A CORPORATION OF NEW YORK

TABULATING MACHINE

Application filed February 18, 1924. Serial No. 693,572.

The present invention is directed to improvements in tabulating machines and more particularly to improvements in printing tabulators.

5 The invention has for its object the provision of a tabulator embodying means for reading the index point designations of record cards preferably by electrical contact brushes, and thereby controlling circuits to 10 magnets which in turn differentially control the displacement of elements which are provided with type and which elements also are adapted to directly set up amounts upon accumulator wheels. When totals are to be 15 printed the accumulator wheels are adapted to differentially control the displacement of the said elements.

Further objects of the present invention reside in the general simplification of the machine as a whole.

A further object of the present invention resides in the provision, in a tabulating machine, of a plurality of elements carrying type and adapted to directly control or to be 20 controlled directly by accumulator wheels, which elements are displaced synchronously with the movement of a card through the machine and are differentially arrested and prevented from further movement upon the passage of index point perforations under the card reading devices.

In the drawings,

Fig. 1 is a front part sectional view of the tabulator counter.

35 Fig. 2 is a vertical transverse sectional view, the section being taken substantially on line 2-2 of Fig. 1.

Fig. 3 is a similar transverse sectional view, the section being taken substantially on line 3-3 of Fig. 1.

40 Fig. 4 is a detail sectional view through the card feeding sensing and stacking mechanism. This section is taken substantially on line 4-4 of Fig. 1.

45 Fig. 5 is a detail view of the start and stop key mechanism together with the drive shaft clutch mechanism. This view is taken substantially from the left of Fig. 2 looking to 50 the right.

Fig. 6 is a detail view of one of the elements which carries the type bars.

Fig. 7 is a perspective view of a record card and the sensing brush therefor.

Fig. 8 is a detail view of the magnetic latch mechanism for differential elements.

Fig. 9 is a detail sectional view of the same mechanism taken substantially on line 9-9 of Fig. 8.

Fig. 10 is a circuit diagram of the machine. 60

Drive for the machine

The drive for the machine may be secured from any suitable source of power such as an electric motor (not shown) which is adapted to rotate a gear 10 (Fig. 5). This gear is fast to one element 11 of a one revolution clutch, the other element 12 of which is fast to the main drive shaft 13 of the tabulating machine. The clutching of these elements together is effected by a suitable spring-pressed dog or latch 14 which is carried by part 12 and adapted to fit into a notch or recess in the element 11. A suitable stop and start key arrangement is preferably provided for controlling the operation of the clutch. Assuming the machine stationary and it be desired to be put into operation, the start key 15 (Fig. 2) is depressed thereby elevating a link 16 and rocking a bell crank 17 counterclockwise. Part 17 carries a latch 18 (Fig. 5) which until rocked out engages a pin upon the clutch dog 14 and maintains it disengaged from its notch. The counterclockwise rocking of the bell crank releases the clutch dog from latch 18 and permits it to engage the notch in element 11 at the proper time in the machine cycle. The machine now continues to run, a suitable pawl 19 holding the parts in displaced position. To stop the tabulator at any time the stop key 20 is depressed thus freeing the pawl 19 from link 16 and permitting a spring 21 to move the parts into position to withdraw the clutch dog at the proper time in the cycle. 70 75 80 85 90 95

If a total is to be taken the tabulator drive shaft should make a single revolution only. For such operation the stop key is first depressed and locked in by a notch 22. This will hold out pawl 19 and thereafter upon 100

depressing the start key 15 the parts will first be displaced to release the clutch and immediately thereafterwards will be restored to reengage the clutch dog upon the completion of one revolution thereby causing the tabulator main drive shaft to make a single revolution.

The main drive shaft or cam shaft 13 of the machine extends to and is suitably geared to 10 a card feeding and stacking device. The driving gearing is best shown in Figs. 3 and 1 and is generally designated 25. Certain of these gears 25 have connected thereto the usual links 26 which actuate a picker 27. The 15 picker 27 is adapted to withdraw one card at a time from a supply stacks 28 (Fig. 4) and advance the same to feed rolls 29 which advance the card past the card reading brushes to the stacker 30. The stacker is of conventional form and delivers the sensed cards to a storage or discharge stack 30a. All of the 20 feed rolls and the stacker are driven by the gearing 25.

Unlike previous electrically controlled 25 tabulating machines, the cards are presented in a different manner to the reading devices. As shown in Fig. 7, the 0 index point perforations are leading and reach the brushes first instead of last as in the so-called Hollerith types of electrical tabulators. The card reading devices include individual and insulated contact blocks 31 and brushes 32 which are preferably electrically connected to a common bar 33. In order to permit high 30 speed tabulating operations to be effected I provide what is here termed a double brush construction. Each brush comprises preferably two sets or bundles of wires marked *a* and *b* in Fig. 7 and the arrangement is such 35 that the time of contact of the brushes to the contact blocks through the holes in the cards is materially prolonged over what it would be with ordinary round brushes of the usual single type. The establishment of circuits 40 through the index point perforations of the record cards is adapted to control the adding and printing operations as will hereafter be described.

The main adding section of the tabulator 50 will now be described. Briefly the principle involved in this machine includes a plurality of elements, one for each column on the card, which elements cooperate to effect both the printing and the accumulation of the number 55 derived from the record card. In order to control the printing and accumulation in accordance with the index point perforation on the card, provision is made for displacing the elements at a speed substantially synchronous 60 with the feed of cards through the machine. It may be here stated that by synchronous is meant not necessarily at an identical velocity to that of the cards but at a correlated velocity which does not vary at one 65 point with respect to the velocity at another

point in the cycle. This velocity may be in itself the same or different from the velocity of the cards passing through the card feeding attachment. The controlling elements being thus moved synchronously with the card feed are arranged to be differentially arrested and prevented from further movement upon an index point perforation passing under the sensing brush. Then at a given time in the 70 cycle, suitable hammer mechanism impacts against the type carried by the elements causing an item to be printed on a record sheet. Subsequently accumulator wheels are 75 meshed with the aforesaid elements and the latter are restored to the normal position thus 80 entering the amounts printed into the accumulators.

Referring now to the drawings, Fig. 2, the synchronously moved elements consist of bars 103 which are suitably guided in frame parts 85 of the machine.

Preferably these bars are made substantially straight and their synchronous movement is one of direct linear translation. The synchronous motion of the bars is effected as follows. Slidably supported in the frame of the machine is an actuating and restoring frame comprising cross bars 40, 41 and 42 (Fig. 2). These laterally extending bars are united by vertical members, such as 44, and this frame assembly is arranged to be reciprocated vertically by a linkage 45 shown in dotted lines in Fig. 2 and having follower rolls cooperating with complementary cams 46 and 47. At the lower end of each element 103 rearwardly extending shoulders 47a are provided. To these shoulders of each element are connected springs 48 which extend upwardly and connect at their upper ends to the cross bar 41. Cross bar 42 acts upon the downward movement of the frame to contact with shoulders 49 on elements 103 and lower them. Upon the upward movement of the frame, cross bar 42 moves away from the shoulders 49 and allows the elements 103 to rise under the tension of springs 48. This spring tension is maintained as the bars 103 rise, by the elevation of the upper anchorage 105 41. As previously explained, the motion of the parts or elements 103 is synchronous with 110 that of the card feed.

Each element 103 at its upper end carries a plurality of type 50 (see Fig. 6). These type are of the usual form used in adding machines and are held by springs away from the printing platen 51. The printing platen 51 is of the usual form and includes the usual feed mechanism indicated at 52 in Fig. 3. Suitable inking ribbon 54 (Fig. 2) is also provided. For striking the type at the printing line a plurality of spring-pressed plungers 55 are provided, which plungers are adapted to be struck by hammers 56. The hammers 56 are impelled against the plungers 55 by springs 57 and restoration of the 115 120 125 130

hammers is effected by means of a bail 58. Tripping of the hammers is effected by pawls 59, 59a and 60 and tripping of the hammers for printing zeros to the right is secured by members 59b. Parts 58 and 59 are actuated by the linkage shown in Fig. 3 and including link 61, bell crank 62 and link 63. Link 63 connects to a bell crank 64 pivoted at 65 and this bell crank is actuated by a linkage and rocker arm 66 which is displaced by a cam 67 fast to the main drive shaft 13 of the machine. The parts just described serve to trip the hammers at the proper time in the cycle and cause an imprint to be made upon the record sheet. To effect paper feed link 70 is provided which operatively connects to the bell crank 62. The cam follower 66 is held against cam 67 by means of a suitable spring 68 best shown in Fig. 3. In this figure also a number of springs 69 are shown which serve to connect cross bar 41 with a fixed frame portion of the machine.

Magnetic latch section

Referring now to Figs. 2, 8 and 9, it will be noted that there are a plurality of magnets marked 71. One pair of these magnets is provided for each column on the record card from which readings are to be taken. In cooperation with each magnet is a pivoted armature member 72. This armature member is preferably provided with pivoted trunnions 73 which are suitably mounted in fixed frame portions of the machine. Each armature 72 has a rearwardly extending hook portion 74 which is notched as best shown in Fig. 9 and adapted to normally engage a stop element 75. The armatures 72 are normally engaged with the stop elements 75 by means of springs 76 (Figs. 8 and 9) and the stop elements in turn are normally urged to the right by tension springs 78 (Fig. 8). The stop elements are slidably guided in the machine frame and at their extreme ends carry multiple-toothed pawl pieces 79 which cooperate with complementary ratchet shape pieces 80 fast to the lower end of the elements 103. The arrangement is such that upon the energization of any magnet 71 the armature latch 74 is released allowing stop piece 75 to move to the right, permitting the ratchet piece 79 to engage with corresponding ratchet piece 80 on the element 103 and thereby arrest and prevent further upward movement of said element. Subsequently the springs 48 on the elements 103 which are arrested yield to a further extent and allow the actuating frame to rise to its maximum high position.

The provision of the cooperating multi-toothed ratchets 79 and 80 has been found particularly effective in arresting the elements 103 and preventing the tendency of these parts to rebound after they are arrested.

Thus it is possible to attain comparatively higher tabulating speeds than before.

At a certain time after the elements 103 have been arrested the stop members 79 are withdrawn from cooperation with the ratchet members 80 and, in order to hold the elements 103 in position until printing is finished and the accumulators engaged, certain locking means are provided. This locking is effected by means of spring-pressed locking elements 75 82 (Fig. 8) which are adapted to be dropped in notches in plates 83 which are fast to the elements 103 upon the counterclockwise rocking of a bail 84. This bail is operated by a linkage 85 connected to a follower 86 which is actuated by a cam 87 on the main drive shaft 13 of the machine.

As in other tabulating machines utilizing electrical circuits through the cards, means must be provided for interrupting the magnet circuits before the brushes leave the holes in the cards. For this purpose, contacts 88 are provided in the card and magnet circuits, which contacts are normally closed. Disposed below the contacts are slider pieces 89 90 having shoulders 91 which engage suitable insulating buttons upon one of the contacts of each pair. The slider pieces are urged away from the contacts by springs 90. The stop pieces 75 have upwardly extending shoulders 91a which align with shoulders on the slider pieces 89. When the stop piece 75 moves to the right upon the energization of magnet 71, the slider piece 89 will correspondingly move and thus open contacts 88 breaking the card 100 circuit and preventing arcing at the brushes. When the stop pieces 75 are restored to the left, the slider pieces 89 are also forced to the left to maintain the contacts 88 closed. This condition is maintained until the stop pieces 105 are again released by the energization of magnets 71. Relatching and restoration of the stop pieces 75 and restoration of the slider pieces 91 to reclose contacts 88 is effected at the proper time in the cycle by means of a restoring bail 92 which is adapted to be displaced to the left from the position shown in Fig. 8 to contact with shoulders 91a on the stop pieces 75. Shoulders 91a are in alignment with the corresponding sliders 91 and thus displace to the left tensioning springs 90 and closing contacts 88. The bail 92 is fixed to a rock shaft 125 which has fast upon it a crank 93 (Fig. 2), which crank through a pin and slot connection is actuated by a bell crank 94 disposed on shaft 120 and having a follower 96 cooperating with a cam 97 fast upon the main cam shaft 13.

Accumulator section

Before describing the detailed accumulator operation it will be explained in general that the accumulator is of the type commonly used in adding machines. In the operation of the machine the type bars or elements 103 rise to 130

a differential position. After they have been arrested the accumulator wheels are enmeshed and the type bars are thereafter restored to their normal or lower position. 5 This restoration of the type bars rolls the amount previously set up upon the type bars into the accumulator wheels. Then, upon the next upward movement of the type bars, the accumulator wheels are again unmeshed to be 10 remeshed when the type bars are arrested. In total printing operations the accumulator engagement is reversed and the accumulator wheels are engaged with the type bars at the beginning of their raising cycle and serve to 15 control the extent to which they are elevated. At the end of the type bar raising cycle in totalling operations the accumulators are demeshed and thus stand at zero ready to accumulate a new total upon the commencement 20 of the next listing operation.

Accumulator

The accumulator which in general details is of the well known Burroughs type comprises the accumulator wheels 101 adapted to mesh with the racks 102 carried on the type bars or elements 103 being connected thereto by a pin and slot connection, as at 104, and being held in a relatively downward position by 25 a spring 105 so that the rack normally engages the lug 106 fixed on the type bar. The accumulator wheels are shown as having twenty teeth and two carrying projections 107. These projections cooperate with a lever 108 pivoted at 109 and adapted when actuated by the counterclockwise rotation of the wheel to turn the latch 110 in a clockwise direction releasing the carrying latch 111 so that the latter may be turned counterclockwise by its spring 112. This as is well known 30 will move the carrying latch 111 out of the path of carrying stop 113 so that the racks may on their downward stroke move one tooth farther to carry one. It is, of course, 35 understood that this carrying takes place in the next adjacent wheel to the left. Once during each machine cycle the shaft 114 is rocked clockwise. This in turn rocks the carrying latch 111 in a similar direction, locking 40 all such latches under the latch 110, which, as is seen, is provided with a spring 115. During normal listing and adding operations, the accumulator wheels are normally in mesh with the racks. Just before the type bars begin 45 to rise a cam 116 fixed on the cam shaft 13 and turning in a counterclockwise direction, actuates a follower 118 on a lever 119, rocking the latter about its pivot 120, raising the pin 121 and depressing pin 122. A T-shaped lever 123 having opposite bifurcated sides is at this time in the position shown in Fig. 2, cooperating with the pin 122 so that the depression of this pin pulls downwardly upon said lever 123 and also rocks the lever 55 124 clockwise about its pivot 125. The lever

124 has pin and slot connection at 126 with the cam bar 127. Thus this cam bar is at this moment depressed, moving the cam 128 downwardly. This in turn pushes the follower wheel 129 to the right. This follower is carried by the arm 130 pivoted at 131 and carrying the shaft 132 on which are mounted the accumulator wheels. Thus said wheels will be moved out of mesh with the racks. While the parts are in this position the type bars and racks rise to position being stopped under control of the perforated card. While the parts are in this latter position, the cam 116 will have turned substantially 180 degrees and the follower 118 will ride down to the lower position of the cam, raising the cam bars 127 and 128 to permit the accumulator wheels to mesh with the racks 102. During the next position of the cycle, the type bars and racks descend to normal position rolling the data into the wheels. All of the racks will be stopped by the engagement of lug 113 with the latch 111, excepting where carrying is to take place and latch 111 has been rocked counterclockwise. In the latter case the racks will descend one tooth space farther and add one to the appropriate accumulator wheels. Before the type bars and racks begin their downward stroke, all of the carrying latches 111 are restored to normal position by clockwise rotation of shaft 114 and carrying the bail 133, which engages the rear end of the latches 111, moving them into locked relation with latch 110. Rocking of shaft 114 is effected by means of a lever 134 fixed thereon and connected by a link 135 to a lever 136, pivoted on shaft 131 and carrying a follower 137 cooperating with a cam 138 on the bar 139. This bar is connected by a pin and slot connection to a lever 140 pivoted at 125 and having a depending arm 141 connected by a link 142 to a lever 143 pivoted at 120 and carrying a follower 144 cooperating with a cam 145. Once each revolution of said cam the raised portion 146 rocks the lever 143 and causes the cam 138 to rise and fall. The rise of said cam permits the follower 137 on the lever 136 to move to the left under the action of a spring 148.

Operation of accumulator for total taking

In taking totals the accumulator must be in mesh with the racks while the type bars will rise to position, the said bars being thus controlled as to the height to which they rise by the accumulators. To take a total the total key 149 (Fig. 3) is pressed to the right. A plate 150 attached to said key is provided with a cam slot 151 into which reaches a pin 152 on a lever 153. Said lever is pivoted at 154 and has a depending arm 155 and a pin and slot connection with a lever 156 (see also Fig. 1) fixed on a shaft 157 on which is also fixed a lever 158 connected by a link 159 to the aforesaid T-shaped piece 123. Thus the 150

actuation of key 149 to the right moves said T-shaped piece 123 from the position of Fig. 2 to that of Fig. 3, causing it, owing to camming action between the side of the depression in the piece 123 and the pin 121 to lower lever 124 and shift cam bar 127 downwardly to force the accumulator wheels out of mesh with the racks 102 so that when the cam 116 rocks lever 119 in a clockwise direction, the 5 cam bar 127 will be raised to permit the accumulator wheels to mesh with the racks. Now when the type bars rise they will rotate the accumulator wheels backward until one of the projections 107 engages the upper portion 10 of the stop 108 and is thus prevented from further rotation. The type bars are thus held in this position and will print the character represented by the position of the accumulator wheels before the commencement 15 of the upward movement of the type bars. The accumulator wheels, on the other hand, will now be in zero position. At this time the cam 116 will permit counterclockwise movement of lever 119 and depress the 20 cam bar 127, moving the accumulator wheels out of mesh with the racks, so that when the latter descends to normal position the accumulator wheels will remain reset at zero. The pressing of the total key 149 is also adapted 25 to raise all of the racks 102, since the reversal of the positions of the cam bar 127 and the accumulator wheels 147 turned the carrying latches 111 out of the path of the lugs 113 and 30 permitted the racks to drop one tooth space. The plate 150 is provided with a second cam 35 notch 160 into which a pin 161 on a lever 162 reaches. The lever 162 is fixed on the shaft 163 which also carries arms 164 cooperating with a bar 165 to raise the latter, which in 40 turn will raise the racks 102. It is while the racks are in this raised position that the accumulators mesh therewith.

Circuit diagram

45 In Fig. 10, wires 170 represent the main circuit leads of the machine. 171 is a suitable double pole switch which, when thrown to closed position, connects the various circuits of the machine to the supply leads 170. 50 Suitably fixed to one of the shafts of the machine which makes one revolution per card cycle are cam contact devices 172 and 173. These cam contact devices are those commonly used in tabulating machines to control 55 the supply of current to the brushes and the magnets controlled thereby only at such times when cards are under the brushes and to interrupt these card and magnet circuits at other times in the cycle, as for example, during the interval between two cards. From 60 cam contact 172, a lead 174 leads to the common brush bar 33. From individual contact blocks 31 individual leads 175 extend to a plugboard 176. In the illustrated embodiment the plugboard, as shown in Fig. 2, com-

prises plug sockets 177 which are connected to the contacts 88. On the circuit diagram (Fig. 10) these connections are indicated at 178. The leads 175 are provided with plugs 179 which may be inserted in the sockets 177. 70 By the use of the plugboard it is possible to plug up any desired field from the record card to any desired set or group of type bars and accumulating elements. Leads 178 extend through the contacts 88 thence through 75 magnets 71, through resistance 180 to common lead 181 which connects back to the line through the cam contact devices 173.

In the use of this tabulator, the general practice to be followed in punching cards will 80 be to punch zeros in all columns in which no adding or printing is to be effected. This will prevent any of the extra type bars from rising above the zero position.

What I claim is—

1. A card-controlled tabulating machine comprising a common element having provisions for positioning a group of type and actuating a correlated accumulator element, means for moving said element synchronously 90 with the feed of cards through the machine, and means controlled by the perforated index point designations of moving record cards for arresting the movement of said element at differential positions according to the relative 95 location of the perforations upon the record card.

2. A tabulator consisting of a common element having provisions for positioning a group of type and actuating a correlated accumulator element, card feeding means, and means for synchronously moving the said element and the record cards, and means for arresting the movement of said element, and means for controlling said last mentioned 100 105 means in accordance with index point perforations in the record card.

3. A tabulator comprising an element which both positions a group of type and actuates a correlated accumulator element, 110 means for moving said element synchronously with the feed of cards through the machine, and magnetic controlled means for arresting the movement of said element at differential positions in accordance with the positions of the index point perforations of 115 passing record cards.

4. A card-controlled tabulating machine comprising an element which both positions a group of type and actuates a correlated accumulator element, means for moving said element synchronously with the feed of cards through the machine, means for reading the index points of record cards while the latter are in motion through the machine, and means 120 controlled by said last mentioned means for arresting the movement of said element at differential positions in accordance with the reading derived from the record cards.

5. The invention set forth in claim 4 in 125 130

which means is provided controlling the displacement of the said element in accordance with the amount standing upon the accumulator whereby said amount may be printed.

6. A tabulating machine including in combination with card feeding mechanism, a plurality of elements with provisions for imparting a rectilinear movement thereto which is synchronized with the feed of cards through the machine, a plurality of type carried by said elements, accumulator wheels adapted to be driven by said elements or to control the displacement of the same in totalling operations, a plurality of magnetic devices controlled by perforations in the cards while the latter are in motion, and means controlled by said magnetic devices for arresting the rectilinear motion of the aforesaid elements at differential positions in accordance with the index point perforations of the record cards.

7. In a cyclically operable record controlled tabulating machine, an accumulating device and a type carrying member, a common operating element for said accumulating device and said member and means for cyclically operating the same synchronously with the operating cycles of the tabulator, record controlled means for arresting the motion of said operating element in differential positions corresponding to data on controlling records and means for coupling said accumulating device to said operating element after its motion is arrested and maintaining the coupling until the operating is restored to its initial position.

8. In a cyclically operable record controlled tabulating machine, an accumulating device and a type carrying member, a common operating element for said accumulating device and said member and means for cyclically operating the same synchronously with the operating cycles of the tabulator, record controlled means for arresting the motion of said operating element in differential positions corresponding to data on controlling records during tabulating cycles, and means for coupling said accumulating device to said operating element after its motion is arrested during such cycles and maintaining said coupling until the operating member is restored to its initial position; means for coupling said accumulating device to said operating element at the beginning of totalizing cycles and means controlled by said accumulating device for arresting the motion of said operating element when said accumulating device reaches home position during such cycles.

9. A record controlled accounting machine comprising record feeding means, a group of type and an accumulating element with a common operating member for positioning said type and accumulating element during accumulating operations and totaling operations, said member being movable synchro-

nously with record feed during accumulating operations and having associated means for interrupting its movement according to index points on controlling records and means for interrupting the movement of said member according to data on the accumulating element during totaling operations.

10. A record controlled accounting machine including record feeding means and record analyzing means, a rack movable synchronously with record feed and means controlled by the analyzing means for interrupting its movement according to index points on records, an accumulating element comprising a pinion, means for demeshing the pinion from the rack prior to record analysis and remeshing the same with the rack after interruption of its movement.

11. A perforated card controlled tabulating machine comprising card analyzing mechanism and means for feeding cards past the analyzing mechanism to permit the successive searching of index points, a type carrier having type corresponding to the several index point positions on controlling cards and means for moving the carrier synchronously with card feed to bring the several type successively into printing position as the corresponding index points on the cards are being analyzed, means controlled by the analyzing mechanism for interrupting the movement of the type carrier when the analyzing mechanism encounters an index point on a card to select the corresponding type for printing and an accumulator element positively driven by the type carrier to the extent of its displacement from normal home position to effect an accumulation of the actual characters printed.

12. A perforated card controlled tabulating machine comprising a card analyzing brush and means for feeding cards past the brush to permit successive searching of index points thereby, a type carrier having type corresponding to the several index point positions on controlling cards and means for moving the carrier synchronously with card feed to bring the several type successively into printing position as the corresponding index points on the cards are being analyzed, an electromagnetically controlled device operated under control of the analyzing brush when it encounters an index point for arresting the movement of the type carrier to select the corresponding type for printing and an accumulator element positively driven by the type carrier to the extent of its displacement from normal home position to effect an accumulation of the actual characters printed.

In testimony whereof I hereto affix my signature.

JOHN ROYDEN PEIRCE.
